(57) CLAIM

I claim the ornamental design for the solar collecting carport, as shown and described.

DESCRIPTION

FIG. 1 is a view from one end of my new design, the view from the other end being identical;

FIG. 2 is a view from one side thereof, the view from the other side being a mirror image of this view;

FIG. 3 is a perspective view from above one end thereof; and, FIG. 4 is a perspective from below one end thereof.

The broken line showing of ground in FIGS. 1 and 2 is for the purpose of illustrating environment and forms no part of the claimed design. The broken line showing of the carport in FIGS. 2 through 4 is for the purpose of illustrating repeating units, and forms no part of claimed design. The carport is shown broken away to indicate that no particular length of carport is being claimed.
